UNITED STATES PATENT OFFICE.

HORACE WYMAN, OF WORCESTER, MASSACHUSETTS, ASSIGNOR TO
CROMPTON & KNOWLES LOOM WORKS, A CORPORATION OF
MASSACHUSETTS.

WEFT-REPLENISHING LOOM.

SPECIFICATION forming part of Letters Patent No. 793,337, dated June 27, 1905.

Application filed October 19, 1904. Serial No. 229,092.

To all whom it may concern:

Be it known that I, HORACE WYMAN, a citizen of the United States, residing at Worcester, in the county of Worcester and State of Massachusetts, have invented certain new and useful Improvements in Automatic Weft-Replenishing Looms, of which the following is a specification.

My invention relates to looms, and particularly to automatic weft-replenishing looms of the class shown and described in United States Letters Patent No. 600,053, of March 1, 1898, in which a magazine or reservoir is provided containing a series of bobbins or filling-carriers which are automatically supplied to the shuttles upon the breaking or exhaust of filling therein in the usual and well-known way.

The object of my invention is to improve upon the construction of the automatic weft-replenishing mechanism ordinarily used in the class of looms referred to.

In my improved filling-carrier magazine, which carries a series of bobbins around its circumference and is adapted to turn or oscillate back and forth about its axis, I provide means for the adjustment of the springs which hold the bobbins seated in their sockets in the supporting-ring of the magazine, so that after the springs have been adjusted to any definite length of bobbin the bobbins will be firmly retained in their seats and correctly alined one with another for the transference of the bobbin into the shuttle. In my improvements I also provide an improved mechanism for turning the magazine about its axis, whereby its operation is rendered more certain and accurate.

My magazine comprises a long sleeve carried on a central stud or pin, said stud supported at its inner end by a stand attached to the loom-frame. On said sleeve adjacent to the supporting-stand and located within the magazine is a gear driven by an angularly-placed bevel-pinion carried on a driven shaft parallel to the loom side. On the outer end of said sleeve is carried a disk or plate provided at its outer edge or circumference with a series of bars projecting inward. To the

ends of said bars is attached a bobbin-head-supporting ring provided with a series of 50 sockets around its circumference to receive and support the heads of the series of bobbins carried by the magazine and leaving a free space inside of the ring between it and the bevel-gear on the sleeve of the magazine for 55 the transerrer to enter within the magazine. Outside of said disk or plate and adjacent thereto is preferably a second disk or plate mounted on the hub of the first-mentioned disk and adapted to be adjusted longitudinally thereon. The circumference of said second disk or plate is provided with a series of channels or recesses to support the tips of the bobbins. These channels coincide with the position of the sockets of the ring which 65 supports the heads of the bobbins. The first-mentioned disk or plate may have a series of channels to support the tips of the bobbins. On the outside of said second disk is preferably carried a series of flat springs, one for 70 each of the channels, which springs press against the ends of the bobbins. By reason of the provision for longitudinal movement of said second disk carrying the springs the pressure of said springs against the tips of 75 the bobbins may be adjusted as desired to hold the heads of the bobbins firmly in their sockets on the ring. I prefer to make the whole disk carrying the springs adjustable; 80 but the individual springs may be adjustable.

My improved construction of the magazine permits of the transerrer being pivoted outside of the bobbins and extending into the magazine on the inner side of the bobbins between the gear on the sleeve of the magazine 85 and the bobbin-head-supporting ring to permit the end of the transerrer when required pushing a bobbin outward and downward into a receiving-shuttle. It also permits of the magazine being rotated in either direction. 90

In my improvements the actuating-shaft which carries the bevel-gear which operates the bevel-gear to rotate the magazine is located at right angles to the axis of rotation of the magazine and between the inner end 95 of the magazine and the loom-arch, so that

I am enabled to extend said shaft at its rear end to a convenient position at the rear of the loom and to mount thereon a compound motion through which the magazine is rotated 5 in a forward direction after the bobbin has been transferred from it to a receiving-shuttle, and also carried either forward or backward, operated from the shifting shuttle-box motion as the shuttle-boxes are moved up or 10 down to position the bobbins, having fillings of different colors to be interwoven in the fabric according as the shifting shuttle-boxes are moved.

In my improvements a spur-gear on one 15 member of the compound motion is actuated by a rack through connections to the shifting shuttle-box motion of the class shown and described in United States Letters Patent No. 764,326, dated July 5, 1904, to rotate the magazine backward or forward as the shuttle-boxes are raised and lowered. A pawl, actuated from a moving part of the loom when a bobbin has been transferred, 20 acts to move the magazine from one division to another division which carries a similar colored bobbin to the one transferred.

In my improvements the supporting-stand for the stud carrying the magazine has a hub for said stud and also has a plate or disk 30 thereon covering the end of the bobbin-head-supporting ring, and also a flange projecting over the outside of the bobbin-heads carried in the sockets of said ring, which flange serves to retain the bobbins from falling. Said stand 35 also carries a hub for the transerrer-lever, and there is an opening through the stand for the transerrer to pass. Said stand also has another opening for the bevel-gear on the driving-shaft, through which opening it engages the bevel-gear on the sleeve of the 40 magazine. The plate or disk on said stand also carries a bearing for the driving-shaft near the pinion carried on it, whereby the pinion on the driving-shaft and the bevel-gear 45 on the sleeve of the magazine are firmly held with their teeth in mesh with each other.

I have only shown in the drawings a detached portion of a loom of the class referred to with my improvements combined therewith 50 sufficient to enable those skilled in the art to which the same belong to make and use the same.

Referring to the drawings, Figure 1 is a sectional elevation of a loom-frame and inner 55 end view of the filling-carrier magazine and operating mechanism embodying my improvements looking in the direction of arrow *a*, Fig. 2. Fig. 2 is a plan view of the filling-carrier magazine and operating mechanism 60 shown in Fig. 1 looking in the direction of arrow *b*, same figure. Fig. 3 is a central vertical section through the filling-carrier magazine shown in Fig. 2 on line 3-3, same figure, looking in the direction of arrow *c*. 65 Fig. 4 is a detached sectional view showing a

modified construction of the springs for the bobbins. Fig. 5 is an outer end view of the opposite end of the loom, showing the connections to the shifting shuttle-box rod; and Fig. 6 is a detached rear view of the connections looking in the direction of arrow *d*, Fig. 5.

In the accompanying drawings, 1 represents the loom sides or frames; 2, the breast-beam; 3, the lay; 4, the lay-sword; 5, the connector 75 from the lay to the crank-shaft 6.

I will now describe my improvements.

7 is a stationary stand, preferably of circular shape, with a foot 7', which is attached by bolts or otherwise on the upper side of the 80 breast-beam, at one end thereof. The stand 7 forms a rigid support for the several parts of the rotary filling-carrier magazine.

A bracket or angle-iron 8 is attached at one end to the loom-arch 9 and at its other end 85 to the upper part of the stand 7 to hold said stand in position. On the stand 7 is formed a hub or boss 7", in which is secured by a nut 10 the reduced end 11' of a stud 11. On the stud 11 is loosely mounted the sleeve 12, which 90 is held on the stud 11 to prevent any longitudinal movement—in this instance by a washer 13 and nut 14 on the outer threaded end of the stud 11. (See Fig. 3.)

Mounted on the outer reduced end of the 95 sleeve 12 is the hub 15' of a circular disk or plate 15. The hub 15' is secured on the sleeve 12 in this instance by a set-screw 16. The circular disk or plate 15 has a series of inwardly-extending arms or bars 15" at its outer 100 edge—in this instance seven in number, which divide it into seven divisions or parts. Upon the inner ends of the arms 15" is attached a ring 17, having therein a series of sockets 17' (see Fig. 3) to receive and support the heads 105 of the bobbins 18. The ring 17 extends within an outwardly-projecting flange 7", which extends around the stand 7, except at the lower part thereof. (See Figs. 2 and 3.) A second circular disk or plate 19 preferably extends 110 upon the outside of the plate 15 and has a hub 19' thereon mounted on the hub 15' of the plate 15 and adjustable longitudinally thereon by means of a set-screw 20. (See Fig. 3.) The plate or disk 19 is provided on 115 its periphery with a series of notches or sockets 19" to receive the ends or tips of the bobbins 18. Secured to the disk 19 is a series of flat or leaf springs 21, the number of said springs corresponding to the number of sockets 19" in said disk. The free end of each spring is adapted to extend into the outer end 120 of each socket to engage the end or tip of the bobbin, as shown in Fig. 3, to hold the bobbin seated in its socket. The tension of the 125 springs 21 on the tips of the bobbins 18 may be adjusted as desired by moving the hub 19' of the disk 19 toward or away from the disk 15 and securing it in its adjusted position by a set-screw 20, thus regulating the dis- 130

tance between the disk 15 and the disk 19, carrying the springs 21.

In Fig. 4 is shown a modified construction of the springs 21. In the construction shown in said figure the second disk or plate 19 is done away with and each spring 21^a is secured upon the disk or plate 15 and the tension of the spring adjusted by means of two screws 21^b, one on each side of a wedge-shaped projection 21^c, against which the attached end of the spring 21^a presses.

22 is a handle having the hub 22', which is secured by a set-screw 23 on the outer end of the sleeve 12, to turn said sleeve and magazine thereon as desired.

24 is a pin secured to the handle 22 by a set-screw 25. The ends of the pin engage recesses in the periphery of the handle 22 and are wound around the pin 24, as is customary.

I will now describe the mechanism for rotating the filling-carrier magazine.

The sleeve 12 has a bevel-gear 26 fast on its inner end and in this instance integral therewith. The bevel-gear 26 extends within a recessed portion of the stand 7 and on the inner side of said stand (see Fig. 3) and is in mesh with and driven by a bevel-gear 27, which extends through an opening 7^a in the stand 7 (see Fig. 1) and is fast on a shaft 28, having a bearing 29 attached to a bracket 30, bolted to the stand 7. (See Fig. 1.) The outer end of the shaft 28 is mounted in a bearing 31 on the upper end of a stand 31, bolted to a bracket 32, secured to the loom-arch 9. (See Fig. 1.)

On the shaft 28 is fast a bevel-gear 33, and a second bevel-gear 34 is loose on the shaft 28. A third bevel-gear 35 is loosely mounted on a stud 36, carried on the ratchet-wheel 37, and extends between and meshes with the two bevel-gears 33 and 34. The ratchet-wheel 37 has a hub loose on the shaft 28 and has a check-wheel 38 attached thereto, which is engaged by a roll 38' on an arm 38", actuated by a spring 38''. (See Fig. 2.)

The ratchet 37 is adapted to be rotated by a pawl 39, pivoted by a pin 39' on one end of an angle-lever 40, which is loosely mounted on the shaft 28. The other arm of the angle-lever 40 is pivotally connected to the upper end of a vertically-moving rod or connector 41. The lower end of said rod or connector is attached to one end of a lever 42, pivoted at 43' on a stand 43 and having a circular portion 42' thereon, adapted to be engaged by a cam 44 on the bottom shaft 45 (see Fig. 1) when said lever 42 is released by the disengagement of the hook end 46' on the lever 46, fast on the rock-shaft 47. (See broken lines in Fig. 1.) Also fast on the rock-shaft 47 is an arm or lever 48, the outer end of which is connected with the lower end of the connector or rod 49. In this instance the rod 49 extends through a hole in said lever 48 and has

a nut 50 thereon to engage the upper side of said arm. A spiral spring 51 encircles the lower end of the rod 49 and bears against a nut 52 adjustable thereon and the lower side of the arm 48. The upper end of the connector 49 is pivotally connected to the supporting-arm 53' of the transerrer 53. The supporting-arm 53' has a hub fast on a rock-shaft 53'' and is bent to extend through an opening 7'' in the stand 7 within the magazine (see Fig. 2) and support the transerrer 53, which extends above and is adapted to engage the lowest bobbin 18. (See Fig. 3.) The transerrer 53 extends within the magazine beyond the bevel-gear 26, as indicated by broken lines in Fig. 1. The downward movement of the transerrer 53 when acting to transfer a bobbin 18 from the magazine into a shuttle in the usual and well-known way will, through its supporting-arm 53', move down the connector 49 and arm 48 and rock the shaft 47 and cause the lever 46 to be disengaged from the lever 42, releasing said lever from its normally inoperative position and allowing it to drop and to be engaged by the cam 44, which as it revolves will raise said lever and through the connector 41 operate the pawl 39 to cause it to engage and rotate the ratchet-wheel 37 and through bevel-gear 35, meshing with and turning bevel-gear 33, rotate the shaft 28, and through bevel-gears 27 and 26 rotate the hub 12, carrying the filling-carrier magazine a certain distance to bring a fresh bobbin into operative position over the running shuttle.

On the shaft 28 is fast a check-wheel 54, having depressions in its periphery to receive a roll 55 on a pivoted arm 56, which is actuated by a spring 57 to hold the roll 55 in engagement with the check-wheel 54 (see Fig. 3) and prevent an accidental rotation of the shaft 28 or parts connected therewith.

I will now describe the mechanism for rotating the filling-carrier magazine in case it is provided with a series of colors, the corresponding colors being arranged in the different divisions of the magazine according to the colors in the drop-shuttle boxes, so that the raising and lowering of the drop-shuttle boxes will cause the rotation of the magazine a sufficient distance to always bring the proper color in position for the action of the transerrer.

The bevel-gear 34, which is loose on the shaft 28 and in mesh with the bevel-gear 35, has in this instance teeth on its periphery which are engaged by the teeth on a longitudinally-moving rack-bar 58, which extends over the gear 34. (See Fig. 6.) The rack-bar 58 is moved by a rod 59, which is attached to a longitudinally-moving rod 60, having bearings 61. The rod 60 has a link 60', adjustably connected thereto at one end, with its other end connected through an angle-lever 62, with a rod 63, adjustably attached at its lower end to a lever 64, pivoted at 65. The lever 64 is

connected, through a rod 66, with the vertically-moving box-rod 67, carrying the shuttle-boxes. (Not shown. See Fig. 5.) The vertical movement of the box-supporting rod 67 will, through the connection to the rack-bar 58, move said rack-bar in one direction or the other and, through gear 34, will rotate the bevel-gear 35 and the bevel-gear 33 to turn the shaft 28 and, through bevel-gears 27 and 26, turn the sleeve 12 of the magazine carrying the filling carriers or bobbins 18 to bring into position to be operated on by the transerrer a bobbin of a color corresponding to the color of the bobbin in the shuttle-box to be thrown through the shed, as will be understood by those skilled in the art.

The operation of my improvements will be readily understood from the above description in connection with the drawings.

20 It will be understood that the details of construction of my improvements may be varied, if desired.

Having thus described my invention, what I claim as new, and desire to secure by Letters 25 Patent, is—

1. In a loom of the class described, a rotary filling-carrier magazine adapted to carry a series of filling-bobbins, said magazine consisting of a disk or plate provided with a series 30 of extended arms or bars having on their ends a bobbin-head-supporting ring, and a second disk or plate contiguous to the first-mentioned disk or plate, said second disk or plate adjustable relative to the first-mentioned disk or 35 plate, and provided with a series of notches or sockets, to receive the ends or tips of the bobbins, and a series of retaining-springs, one for each bobbin, substantially as shown and described.

40 2. In a loom of the class described, a rotary filling-carrier magazine, comprising a bobbin-head socket-ring, and a bobbin-tip-supporting disk, in combination with a rotary sleeve having a gear fast on its inner end, said gear located within the filling-carrier magazine and on the inside of the magazine-stand, substantially as shown and described.

3. In a rotary filling-carrier magazine, a rotary sleeve having at one end a gear located 50 within the magazine to rotate said sleeve, and at its other end two independent disks or plates, adjacent to each other, one of said disks carrying the socket-ring adapted to support the heads of a series of filling-bobbins, 55 and the other adapted to support the tips of the filling-bobbins, substantially as shown and described.

4. In a loom of the class described, a rotary filling-carrier magazine adapted to carry a series 60 of filling-bobbins, comprising a rotary sleeve carrying at one end two disks or plates adjacent to each other, one of said disks carrying the socket-ring adapted to support the heads of the bobbins, and the other disk adapted to support the tips of the bobbins, and said

rotary sleeve having at its opposite end a gear fast thereon, located within the magazine, and through which gear said sleeve is rotated, and also the magazine, substantially as shown and described.

5. In a loom of the class described, a rotary filling-carrier magazine adapted to carry a series of bobbins, comprising a rotary sleeve and supporting means carried at one end for the heads and tips of a series of bobbins, and a gear at the opposite end of said sleeve located within the ring for the heads of the bobbins, and through which gear said magazine is rotated, substantially as shown and described.

6. In a loom of the class described, a rotary filling-carrier magazine, comprising two disks or plates adjacent to each other, and carried on a central rotary sleeve, and said sleeve having a gear fast thereon and located within the magazine, and one of said disks adjustable and provided with slots and springs for the tips of the bobbins, and the other of said disks carrying a ring which encircles said gear, and is provided with sockets for the heads of the bobbins, substantially as shown and described.

7. In a loom of the class described, a rotary filling-carrier magazine carried on a rotary sleeve, and said sleeve mounted on a stud supported at one end by a stand or plate on the loom-frame, and said stud and stand, and a gear fast on said sleeve adjacent to said stand, and on the inner side thereof, a pinion meshing with said gear, and a driven shaft carrying said pinion and extending at right angles to the axis of rotation of said sleeve, substantially as shown and described.

8. In a loom of the class described, a rotary filling-carrier magazine having a gear fast on one end of its supporting-sleeve, and said gear and sleeve, and a bobbin-head-supporting ring located at the same end of the sleeve as said gear, and encircling said gear, leaving a space between said gear and ring for the supporting-arm of the transerrer, substantially as shown and described.

9. In a loom of the class described, a filling-carrier magazine, a stand or support provided with a hub for the supporting-stud of the magazine, and a bearing for a driving-shaft on said stand, a bevel-gear for rotating the magazine on the sleeve of the magazine and adjoining said stand, an angularly-placed driving-shaft, a bevel-gear thereon, adjoining said bearing, to mesh with the gear of the magazine, substantially as shown and described.

10. In a loom of the class described, a rotary filling-carrier magazine, having a gear at one end of its supporting-sleeve, and said sleeve and gear, an actuating-shaft having thereon a gear to move said gear, a compound gear movement carried on said shaft, comprising two independently-moving members, one of which, when actuated will move said magazine forward, and the other will move said

magazine in either direction, substantially as shown and described.

11. In a loom of the class described, a stand for a filling-carrier magazine having a hub for the supporting-stud of the magazine, and a lip or flange extending out from the outer edge and partially encircling said stand, and an opening for the transferrer-supporting arm to pass through, and another opening for a gear to extend through, substantially as shown and described.

12. In a loom of the class described, the combination with a rotary filling-carrier magazine, an actuating-shaft, connections intermediate said shaft and magazine to rotate the same, and a compound gear movement carried on said shaft, of the shuttle-box-lifting rod, and connections intermediate said rod and a gear of said compound gear movement, to communicate the movement of the box-lifting rod to the actuating-shaft, to rotate the magazine in either direction, said connections comprising a rack-bar, a longitudinal moving rod, a connector to an angle-lever, and said lever, a connector therefrom to a lever, and said lever, and a connector therefrom to the lifting-rod, substantially as shown and described.

13. In a loom of the class described, the combination with a rotary filling-carrier magazine, an actuating-shaft, connections intermediate said shaft and magazine to rotate the same, a compound gear movement carried on said shaft, a pawl-and-ratchet mechanism, for operating said shaft, connections from said pawl to a lever operated by a cam, and said lever, of a rocking arm adapted to engage said lever to hold the same out of engagement with its operating-cam, an arm connected with said rocking lever, and connections therefrom to the bobbin-transferrer, and said transferrer,

the movement of which to engage a bobbin, acts to move the rocking arm while in engagement with the cam-lever to release the same, substantially as shown and described.

14. In a loom of the class described, the combination with the actuating-shaft of the rotary filling-carrier magazine, and the actuating-lever for the vertically-moving box-rod, of intermediate connections, whereby the movement of said lever will rotate said shaft to communicate to said magazine a rotary movement, corresponding to the vertical movement of said box-rod, substantially as shown and described.

15. In a loom of the class described, the combination with the actuating-shaft of the rotary filling-carrier magazine, said shaft extending at right angles to the axis of rotation of the filling-carrier magazine, and extending to the rear of the loom, and the vertically-moving box-rod, of intermediate connections, whereby the movement of said rod will rotate said shaft, to communicate to said magazine a rotary movement in either direction, corresponding to the vertical movement of said box-rod, substantially as shown and described.

16. In a loom of the class described, the combination with the vertically-moving box-rod, and the actuating-shaft of the rotary filling-carrier magazine, said shaft extending at right angles to the axis of rotation of said filling-carrier magazine, of connections intermediate said box-rod and said shaft, said connections located at the rear of the loom, and one member of said connections being adjustable, substantially as shown and described.

HORACE WYMAN.
